(73) Assignee: **Clover Mfg. Co., Ltd.**, Osaka (JP)

(57) **CLAIM**

I claim the ornamental design for a sliding diagonal gauge for handicrafts, as shown and described.

(**) Term: **14 Years**

DESCRIPTION

(21) Appl. No.: **29/465,332**

FIG. 1 is a perspective view of a sliding diagonal gauge for handicrafts according to my design, the gauge including a ruler and a slider which is slidable on the ruler;

(22) Filed: **Aug. 27, 2013**

FIG. 2 is a front view of the same gauge;

(51) LOC (10) Cl. **10-04**

FIG. 3 is a rear view of the same gauge;

(52) U.S. Cl.

FIG. 4 is a left side view of the same gauge, which is symmetrical to a right side view;

USPC **D10/65; D15/77**

FIG. 5 is a top plan view of the same gauge;

(58) **Field of Classification Search**

FIG. 6 is a bottom view of the same gauge;

USPC D10/46, 65; D15/66, 77

FIG. 7 is another front view of the same gauge with the slider moved to a distal end of the ruler; and,

See application file for complete search history.

FIG. 8 is a front view of a modified ruler that is replaceable for the ruler of the gauge shown in FIGS. 1-7.
